UNITED STATES PATENT OFFICE.

JOHN M. PETERSON, OF CHICAGO, ILLINOIS, ASSIGNOR TO GEORGE J. SAYER, OF CHICAGO, ILLINOIS.

VALVE MECHANISM.

1,278,006.

Specification of Letters Patent.

Patented Sept. 3, 1918.

Application filed March 23, 1917. Serial No. 156,832.

To all whom it may concern:

Be it known that I, JOHN M. PETERSON, a citizen of the United States, residing at Chicago, in the county of Cook and State 5 of Illinois, have invented a certain new and useful Improvement in Valve Mechanism, of which the following is a full, clear, concise, and exact description, reference being had to the accompanying drawings, forming a 10 part of this specification.

My invention relates to control valves, and has for its object the provision of a valve of this character adapted in its operation to control a plurality of passages 15 successively.

Other objects of the structure will be more clearly apparent from a detailed description of carrying out one form of my invention, which I will now give in connection with the accompanying drawings illustrating the same, in which—

Figure 1 is a side view of my improved valve structure;

Fig. 2 is a side view of the valve structure 25 looking at the opposite side to that of Fig. 1;

Fig. 3 is a top view of my improved valve structure;

Fig. 4 is a sectional view along line 4—4 30 of Fig. 3;

Fig. 5 is a sectional view on line 5—5 of Fig. 4;

Fig. 6 is a sectional view on line 6—6 of Fig. 4;

35 Fig. 7 is a sectional view on line 5—5 of Fig. 4, the parts being in different position from that shown in Fig. 5;

Fig. 8 is a sectional view on line 8—8 of Fig. 4; and

40 Fig. 9 is a sectional view on line 6—6 of Fig. 4, the parts however occupying an alternate position to that shown in Fig. 6.

My improved structure consists of the casing 10 within which is rotatably mounted 45 the valve proper 11. This valve carries at its upper end a plate 12 from which projects the handle 13. The plate 12 has a plurality of notches 14 with which the lug 15 carried by the spring pressed lever 17 operates. The lug 15 is normally held in 50 engagement with these notches by the spring 16. This lug 15 also co-operates with the stops 18 and 19 to limit the movement of the valve.

55 In Fig. 3 the valve handle 13 is shown in

its neutral position. From this it will be seen that the valve can be moved forty-five degrees in a contra-clockwise direction by one step and may be moved by two steps of forty-five degrees each through an arc of 60 ninety degrees in a clockwise direction. The plate 12 likewise has locking lugs 20 and 21 co-operating with a projecting lug 22 carried by the slide rod 23. The slide rod 23 may be slidable on any suitable stationary part of the machine to which the valve structure is attached. This slide rod is controlled so that the lug 22 is normally between the lugs 20 and 21 and prevents movement of the valve handle 13. As soon 65 as the slide rod is moved inwardly as shown in Fig. 3, to disalign the lug 22 from the lugs 20 and 21, then the valve handle 13 may be moved either clockwise or contra-clockwise as the case may be. 70

The valve proper 11 has a control passage 25 which is preferably Y shaped, one branch of which extends clear across said valve from one side to the other. The valve further has the passage way 26 extending 80 clear across, having however at one extremity a restricted passage 27. A passage 28 communicates with the passage 26 and extends at right angles thereto. The valve furthermore has the large exhaust passage 85 29 extending clear through. The valve casing 10 has various ports consisting respectively of the inlet port 30 adapted to supply fluid under pressure, the exhaust port 31, the port 32 leading to a device to which 90 pressure may be supplied, the port 33 leading to another device to which pressure may be supplied, and the exhaust port 34. The port 32 preferably leads to a device to which pressure may be supplied and the port 31 95 co-operates with that same device as an exhaust port. The port 33 is adapted to lead to a second device to which pressure is to be supplied, and the co-operating exhaust port therefor is the port 34. The port 30 is designed to permit the supply of pressure to the valve structure for distribution in accordance with the above. 100

The normal position of the device is shown in Figs. 1, 2, 3 and 7. Under these 105 conditions it will be seen that the passage-way 29 permits exhaust from the port 33 through the port 34. It will also be seen that by means of the passageways 28 and 26, the port 32 is connected with the exhaust 110

port 31. The port 30 under these conditions is entirely closed off as neither passageway 26 nor 25 communicates therewith. Now when the handle 13 is moved into the first 5 forward position, which is shown in Fig. 5, then fluid under pressure is supplied by means of the passageway 26 from the inlet port 30 through the port 32 to one of the devices to be operated thereby. Under this 10 condition of things the port 33 is still exhausting by way of the passageway 29 through the port 34.

The second forward position, which is also the last, is shown in Fig. 6, wherein 15 passageway 26 still connects the inlet port 30 with the port 32 to maintain the pressure on the device connected therewith, but at the same time passageway 25 connects the inlet port 30 with the port 33 leading to the 20 second device controlled by the valve.

It will thus be seen that the first movement of the handle supplies pressure to one device and the second movement supplies pressure to a second device, the first device 25 still remaining supplied with fluid under pressure. During the reverse movement of the handle 13, of course, the positions occupied are the same as those outlined for the forward movement. Should the handle 13 30 be moved contra-clockwise from its neutral position into its only reverse position, then the various passageways occupy the position shown in Fig. 9. Under this condition of things the port 33 is not connected with an 35 exhaust passage, but fluid under pressure is supplied through the passageway 25 from port 30 to the port 33, thus to operate but one of the instrumentalities instead of the two first outlined. The inward portions of 40 these ports 30 and 32 flare so that the passage 25 may communicate therewith when placed in alinement. The passages 30 and 33 extend toward the passage 25 as shown in Fig. 4 so that said passage may intersect 45 said ports and accomplish the proper connections.

It will thus be seen that by properly arranging the various port passages in the valve casing and effecting a corresponding 50 structure of the valve 11 that two pressure operated devices may be successively controlled at one time, whereas but one need be operated with another position of the valve.

From the foregoing which illustrates 55 merely one of the uses to which my invention may be put its general nature will be apparent to those skilled in the art, and having thus described one form which my invention may take, what I claim as new and 60 desire to secure by Letters Patent is:

1. A valve structure of the character described comprising a valve casing and a valve therein, said valve casing having a pressure inlet port, an exhaust port and two 65 outlet ports, and said valve having passage-

ways whereby said pressure inlet port may be connected to said outlet ports successively and then remain in connection with both said outlet ports when said valve is moved in one direction, and said pressure inlet port 70 may be connected with only one of said outlet ports when the valve is moved in the opposite direction.

2. A valve structure of the character described comprising a valve casing and a 75 valve therein, said valve casing having a pressure inlet port, an exhaust port and two outlet ports, and said valve having passageways whereby said pressure inlet port may be connected to said outlet ports successively 80 when said valve is moved in one direction, and said pressure inlet port may be connected with only one of said outlet ports when the valve is moved in the opposite direction, and whereby said outlet ports are permitted 85 to exhaust when said valve is in its neutral position.

3. A valve structure of the character described comprising a valve casing and a valve therein, said valve casing having a 90 pressure inlet port, two exhaust ports and two outlet ports, and said valve having passageways whereby said pressure inlet port may be connected to said outlet ports successively when said valve is moved in one 95 direction, and said pressure inlet port may be connected with only one of said outlet ports when the valve is moved in the opposite direction, and whereby said outlet ports may be respectively connected with their co- 100 operating exhaust ports when the valve is in neutral position.

4. A valve structure of the character described comprising a valve casing and a valve therein, said valve casing having a 105 pressure inlet port, an exhaust port and two outlet ports, and said valve having passageways whereby said pressure inlet port may be connected to said outlet ports successively when said valve is moved in one direction, 110 and said pressure inlet port may be connected with only one of said outlet ports when the valve is moved in the opposite direction, and whereby said outlet ports are permitted to exhaust when said valve is in 115 its neutral position, said passageways in said valve consisting of one passageway extending completely from side to side of said valve, a substantially T-shaped passageway having a restricted opening at one extremity, and a second passageway extending 120 nearly from side to side of said valve.

5. A valve structure of the character described comprising a valve casing and a valve therein, said valve casing having a 125 pressure inlet port, two exhaust ports and two outlet ports, and said valve having passageways whereby said pressure inlet port may be connected to said outlet ports successively when said valve is moved in one 130

direction, and said pressure inlet port may be connected with only one of said outlet ports when the valve is moved in the opposite direction, and whereby said outlet ports 5 may be respectively connected with their co-operating exhaust ports when the valve is in neutral position, said passageways in said valve consisting of one passageway extending completely from side to side of said 10 valve, a substantially T-shaped passageway

having a restricted opening at one extremity, and a second passageway extending nearly from side to side of said valve.

In witness whereof, I hereunto subscribe my name this 10th day of March, A. D. 1917. 15

JOHN M. PETERSON.
